UNITED STATES PATENT OFFICE

2,032,386

PROTECTIVE PAPER PACKAGE

Frank S. Wood, Newton, Mass.

Application December 11, 1933, Serial No. 701,939

3 Claims. (CL. 229—87)

The packaging of goods has become a general custom, almost an art, and the imitation of famous brands, a racket. The prevention of imitations, substitutes and counterfeits, are the objects of this invention. Those objects are obtained by means of the materials with which the package is wrapped and sealed as will be hereafter described.

It is fundamental, in this invention, that the first protection must be given the paper out of which the package is made, and I call attention to several patents that have recently issued or been allowed to me for safety paper and processes of making No. 1,900,067 March 14, 1933; No. 1,939,378, December 12, 1933; No. 1,951,076, March 13, 1934; and Serial Number 552,550 application allowed December 1, 1933. It is upon this paper and its evolution into protective paper that I rely for some of my protective paper.

Safety paper is known to the trade and the art as being, strictly, a special kind of writing paper; and while there is nothing to hinder the use of writing paper for wrapping packages, as a matter of fact, writing paper and wrapping paper are two different classes of goods. Therefore, I define protective paper as an evolution of safety paper especially adapted for packaging, both having certain characteristics in common and differing widely in others. Thus, while safety paper could be used for protective paper, by no possibility may wrapping paper be used, commercially, for writing paper.

While the patents above mentioned describe certain desirable characteristics elsewhere set forth that a protective paper should have, there are other and later developments that are better.

In Patent No. 1,900,067 issued to me March 14, 1933, is described and specified a paper meeting all the essentials of a protective paper, subject to the differences of furnish between a writing paper and a wrapping paper, and the differences in formulas required to make the adaptation.

A specific object of this invention is to seal a paper package so that it cannot be unsealed without destroying the wrapper or discoloring it; and since it would be easy to counterfeit an ordinary paper wrapper, a controlled protective paper with my dual or safety seal is the most effective way of identifying an original package, while a seal that cannot be broken without leaving evidences of tampering is the only means of making a protective paper unbeatable. No matter how good the protective paper might be, if the seal could be broken and the contents tampered with or replaced, the paper would be a worthless

protection. It should thus be clear that both the identifying paper and the safety seal are equally important.

The present state of the art has conclusively demonstrated that the color blue is of a higher vibration or wave length than the color green, also that white is the perfect reflection of all colors. In obtaining the results just described which are caused by chemicals, I know of no way to ascertain whether those results come from the raising or lowering of vibration of a chemical composition or whether it does something to paper that causes its reflective power to break down, with age, under controlled conditions. Then, again, it may be due to the action of cosmic rays, of which little is known.

There is a universal male and female or positive and negative principle that illustrates the two essential factors of my invention. The protective paper is the receptive or negative member that is acted upon, and the dual seal is the active or positive member that produces a union between the two members that cannot be broken without either destroying the female member or giving it a hideous discoloration.

My invention includes two steps in the sealing process: 1st, the melting of paraffin or its equivalent and the dissolving therein of a small quantity of oil-soluble coloring matter; and 2d, the application of this melted paraffin-color in the form of a narrow band or striped coating to a wider band of adhesive or glue while still wet and after said glue has been applied in any desired way. When thus applied, the two form a dual seal and unite the two portions of protective paper to be sealed, so strongly, that it cannot be unsealed by any other means than steaming without destroying the paper wrapper; and any heat in excess of 140° melts the paraffin which penetrates the paper and acts as a carrier for the dissolved color, leaving irremovable evidences of tampering.

Specifically, by protective paper, I mean any of my safety papers, patented or otherwise, or evolutions thereof that I may use as the protective paper member of this invention or any other paper having more desirable protective qualities. This may be of any color or tint and that has the attribute of identifying itself by a simple chemical test or by means of ultra violet rays. In this regard, my ink set papers, patented, provide self identification by writing upon them with any permanent ink and then using any commercial eradicator comprising a weak acid and a chlorine solution. If eradication sets the ink, the pro-

5 tective paper establishes the fact that it is the original package. If the ink does not set, it is not the original package but a substitute or imitation. Ultra violet rays demonstrate the same 10 thing in a different way. In addition I may also use as the protective paper member of this invention, papers that are described in pending applications, and I also intend to use other available 15 papers.

10 Another equally important factor in this invention is the proper sealing of the package, for the reason that a dual seal supplies essential safeguards against tampering and provides detection features that will now be described.

15 I am aware that a small amount of paraffin when applied to paper prevents it from sticking to many things. I am also aware that the mixing of certain proportions of paraffin with certain proportions of resin makes it adhere to paper under the application of heat. But I believe that 20 I am the first to use a mixture of melted paraffin and an oil soluble dye in such proportions as to cause the paraffin mixture to act as a dual or safety seal when a narrow strip of it has been 25 superposed upon a wider strip of glue or its equivalent. Whether the melted paraffin-dye mixture instantly becomes a solid or not when applied to the glue, and whether or not it coagulates instantly when superposed on a strip of 30 wet glue, is a technical point; but it does instantly cease to be a liquid, it ceases to spread over the surfaces that it contacts, and it seals paper, under such conditions, which is brought in contact with it. If this were not true, the 35 paper contacting the narrow band of paraffin-dye would not be sealed. A careful dissection of such a seal proves that it is sealed. This is no more surprising than that paraffin seals the glass jar of the housewife's preserves. It has been determined by instruments of precision that this is a 40 permanent condition under temperatures of less than 140°; but at and above that temperature the paraffin melts, permeates the paper, and acts as a carrier of the oil soluble dye that dis- 45 colors the paper hideously.

After the goods have been wrapped in the protective paper, it is necessary to seal the package at the top, bottom, and along one side where the overlapping edge comes. At these points, any 50 strongly adherent glue or its equivalent may preferably be used and applied in the usual way. See drawing. Fig. 1 shows a sheet of paper to the right hand stippled edge of which a band of glue 2 has been applied; and to this a narrower 55 band of melted paraffin in which has been dissolved an oil soluble coloring member; these two bands create a safety seal for said paper. Fig. 2 shows a box that has been wrapped and safety sealed. The horizontal band 3 shows the outline 60 of the paraffin stripe on the sealed package while the vertical band 3 shows the discoloration that takes place when subjected to a temperature of 140° or more. To this band of glue 2 is applied a narrower band 3 of a dual adhesive that is 65 prepared by adding a small quantity of oil soluble coloring matter to melted paraffin or its equivalent. It is obvious that this may be confined to one color or that a plurality of colors in separate containers may be used. When paraffin, 70 in liquid form, is applied to the glue, it coagulates in cooling and thus prevents the color from spreading outside the narrow band. The glued edges of the protective paper are now pressed together and the package is sealed. On account 75 of the high degree of adherence provided by the

dual seal, the only way that the package may be opened without tearing the paper is by the application of moist heat to the sealed strip. It is obvious that any tearing of the paper leaves behind it danger signals which serve notice that the package has been tampered with. When any moist heat, such as steam, is applied to the seals for the purpose of unsealing, the paraffin melts at the temperature of 140° Fahrenheit, and becomes a liquid. This contains the coloring material in solution and the then liquid solution spreads and permeates the paper causing discolorations which irreparably brand the package as having been tampered with.

10 Dual seal or dual adhesive is the same thing. It 15 is applied as follows: First the glue is applied to the paper by means of a brush; second, the melted paraffin in which has been dissolved the oil soluble coloring matter is applied with a narrower brush to the band of glue that has been applied to 20 the paper. The paraffin with its color carrier coagulates instantly and does not run either into the glue or the paper. Should the contents of the package be removed from its original wrapper and another wrapper substituted, 25 an ink test with eradication serves notice that the contents are not in its original package for the reason that ink written upon any other than the original protective paper, instantly disappears with the use of eradicator. 30 Since the protective paper is made of a special type solely for the manufacturers of the goods in the original package, it will be most difficult to imitate or counterfeit for the same reasons that the paper upon which government currency is 35 printed is not easy to obtain for the purpose of counterfeiting. This purpose could only be brought about with the co-operation of a paper-mill with racketeers and the infringing of patents and the employment of men skilled in the art of 40 making those patented goods as well as the trade secrets surrounding them, a highly improbable occurrence.

What I claim as my invention and desire to obtain Letters Patent for is:

45 1. A protected paper package comprising an impressible member provided with such visible identifications of the original package as to produce a non-duplicatable condition therein, and an active sealing member consisting of glue or its equivalent and an oil-soluble dye dissolved in melted paraffin adapted to seal said original package so as to produce a dual or safety sealed condition that cannot be unsealed without either destroying or discoloring said impressible member, 55 said active sealing member being of a nature to show discoloration in said impressible member when its temperature is raised to 140° or more Fahrenheit.

60 2. A protective paper package comprising an impressible member provided with such invisible identifications of the original package as to produce a non-duplicatable condition therein, and an active sealing member consisting of glue or its equivalent and an oil soluble dye dissolved in 65 melted paraffin adapted to seal said original package so as to produce a dual or safety sealed condition that cannot be unsealed without either destroying or discoloring said impressible member, said sealing member being of a nature to show 70 discoloration in said impressible member when its temperature is raised to 140° or more Fahrenheit.

75 3. A protective paper package comprising an impressible member provided with such visible

and invisible identifications of the original package as to produce a non-duplicatable condition therein, and an active sealing member consisting of glue or its equivalent and an oil soluble dye dissolved in melted paraffin adapted to seal said original package so as to produce a dual or safety sealed condition that cannot be unsealed without

either destroying or discoloring said impressible member, said sealing member being of a nature to show discoloration in said impressible member when its temperature is raised to 140° or more Fahrenheit.
